CLAIM

The ornamental design for a control housing, as shown and described.

DESCRIPTION

FIG. 1 is a front and right side perspective view of the control housing;

FIG. 2 is a front elevation view thereof;

FIG. 3 is a right elevation view thereof;

FIG. 4 is a left elevation view thereof; and,

FIG. 5 is a top plan view thereof.

No claim is made to ornamentation on the bottom or rear view of the control housing.

The features shown in broken lines depict environmental subject matter only and form no part of the claimed design.
